DESIGN FOR A SPACE COOLER CABINET
OR THE LIKEJohn H. Schreiber, St. Louis, Mo., assignor to
General Engineering & Manufacturing Com-
pany, St. Louis, Mo., a corporation of Missouri

Application April 1, 1947, Serial No. 138,097

Term of patent 7 years

(Cl. D62—4)

To all whom it may concern:

Be it known that the undersigned, John H. Schreiber, a citizen of the United States, residing in the city of St. Louis, State of Missouri, has invented a new, original, and ornamental Design for a Space Cooler Cabinet or the like, of which the following is a specification, reference being had to the accompanying drawing, forming a part thereof, in which:

The figure is a perspective view of a space cooler cabinet, showing my new design, the two sides at the rear being identical with the two sides shown.

The characteristic features of my design for the cabinet disclosed reside in the two groups of louvers running completely around said cabinet and having the configurations and arrangement as shown.

I claim:

The ornamental design for a space cooler cab-
inet or the like, substantially as shown and de-
scribed.

JOHN H. SCHREIBER.
